UNITED STATES PATENT OFFICE.

GEORGE LEWIS HOGAN, OF NEW YORK, N. Y.

DESIGN FOR A CASING FOR CLOCKS AND VENDING-MACHINES.

41,320.

Specification for Design.

Patented Apr. 18, 1911.

Application filed January 18, 1911. Serial No. 603,397. Term of patent 3½ years.

To all whom it may concern:

Be it known that I, GEORGE LEWIS HOGAN, a citizen of the United States, residing in the borough of Manhattan, city, county, and State of New York, have invented a new, original, and ornamental Design for a Casing for Clocks and Vending-Machines, of which the following is a specification, reference being had to the accompanying drawing, forming part thereof.

Figure 1 is a front view of a casing for clocks and vending machines showing my design; and Fig. 2 is a side elevation.

What I claim is—

The ornamental design for a casing for clocks and vending machines as shown.

GEORGE LEWIS HOGAN.
